(57) **CLAIM**

The ornamental design for a display screen of an infusion device with graphical user interface, as shown and described.

DESCRIPTION

The sole FIGURE is a front view of a display screen of an infusion device with graphical user interface showing my new design.

The outermost broken-line rectangle shows the perimeter of a display screen or a portion thereof and forms no part of the claimed design. The remaining broken lines illustrate portions of a graphical user interface and form no part of the claimed design.
